CLAIM

The ornamental design for a pair of pet treat camera, as shown and described.

DESCRIPTION

FIG. 1 is a perspective view of the pet treat camera;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top elevational view thereof; and,

FIG. 7 is a bottom elevational view thereof.

Broken lines are used in several of the figures and are used to illustrate environment or structure that forms no part of the claimed design.

1 Claim, 7 Drawing Sheets
